UNITED STATES PATENT OFFICE.

WILSON BARR, OF TRENTON, ONTARIO, CANADA.

ACCOUNT-FILE.

1,361,665.

Specification of Letters Patent. Patented Dec. 7, 1920.

Application filed February 28, 1920. Serial No. 362,152.

To all whom it may concern:

Be it known that I, WILSON BARR, of Trenton, in the county of Hastings, Province of Ontario, Canada, have invented certain new and useful Improvements in Account-Files, of which the following is a specification.

This invention relates to improvements in account files of the type shown and described in my prior United States Patent No. 996197 dated June 27th, 1911, in which a series of frames hinged together in the form of a hook are supported in a casing so that they may be turned up or down on horizontal axes to expose either side of each leaf, and my object is to simplify the constructions for guiding and supporting the leaves, to provide simple, strong and easily operated means for introducing or removing the book of leaves, and to arrange the apparatus so that books containing any desired number of file leaves, within certain limits, may be employed in any one cabinet.

I attain my object by means of the constructions hereinafter described and illustrated in the accompanying drawings in which—

Figure 1 is a side elevation of my improved account file, partly in section, showing the book of leaves in an approximately vertical position and the restraining bars raised;

Fig. 2 a similar view from the opposite side of part of the apparatus showing the restraining bars in their normal operative position;

Fig. 3 a section on the line *a—a* in Fig. 1; and

Fig. 4 a detail in front elevation showing the engagement of the leaves with the restraining bars and guides; and

Fig. 5 a detail showing particularly one of the links, and projection thereon, connected to the lower corner of the front leaf.

In the drawing like numerals of reference indicate corresponding parts in the different figures.

1 is the casing suitably shaped to support the different parts. 2 are the bill-holding leaves connected together by the hinges 3 in the form of a book. The last leaf of the book is supported, by the engagement of its upper part with some stationary part, to prevent it tipping backward. In the preferred form I secure to the upper part of

its sides the pivot pins 4, which, when the book of leaves is in position, lie in open bearings at each side of the casing. These bearings are preferably formed in the following manner so that the casing is adapted to receive books containing a greater or lesser number of leaves as may be necessary.

Bars 5 are suitably supported in a fore and aft position, one at each side of the casing near its upper end. To each bar is secured a plurality of short stops 6 at different distances from the front of the apparatus. A longer stop 7 is detachably secured to each bar 5 by means of bolts 8, a plurality of sets of bolt holes for said bolts being provided in each bar so that the longer stops 7 may be secured to the bar to coöperate with any one of the short stops 6. When the apparatus is in use, the pivot pins 4 lie in front of the stops 7 and behind one set of the stops 6 as shown, so that when the pivot pins are raised out of the open bearings as herein-after described, the leaves of the book will not tilt backward but may tilt forward.

It will be noted that the bars 5 are of angle bar section, the flanges 38 thereof extending horizontally inward forming the bottoms of the open bearings. These flanges will hold up the back leaf, by engagement with the pins 4 if the book is overloaded with accounts so that the weight causes the spring supported table 9 to sag a little. The leaves are supported on the table 9, which is resiliently supported to move vertically. While any suitable means may be provided for yieldingly supporting the table, I prefer the mechanism shown. A pair of bent levers 11 are pivoted on the sides of the casing and are connected by the cross bar 12 on which are journaled roller 13 engaging the underside of the table 9. One or more coil springs are provided, each connected at one end to the lower end of one of the levers 11, and at the other end to the casing. A second pair of levers 14 are pivotally connected to the sides of the casing connected by a cross bar 15 provided with rollers 16 engaging the under side of the table at the opposite end to the rollers 13. The levers 14 are connected with the levers 11 by the pivoted links 17, whereby the levers move together and impart a similar movement to each of the cross bars 12 and 15. The table is guided vertically by means of suitable projections 18, preferably formed as rollers, which en-

100
105
110
115

gage opposite sides of the guide bars 19, one of which is secured to the casing at each side thereof.

To prevent the leaves being forced up beyond their normal operative position when either horizontal or vertical, I provide each leaf at each side of its hinge with a projection 20, preferably formed as a roller. These projections are adapted to engage the under 10 sides of the restraining bars 21 which are supported one at each side of the casing in such a manner as to be vertically adjustable, or otherwise moved from engagement with the projections 20.

15 When the restraining bars are in the position shown in Fig. 2, the projections 20, when the leaves are in the upright position, engage beneath the restraining bar, while as each leaf is drawn down to the horizontal 20 position its projections move downwardly and lie behind the vertical guide bars 19. As the leaves are turned down pressure is exerting on the vertically movable table tending to depress it as much as may be necessary 25 to accommodate the number of leaves which have been drawn down from the vertical to the horizontal position.

Forward displacement of the leaves is, of course, prevented by the engagement of the 30 projections 20 with the rear sides of the vertical guide bars 19. It is desirable also to prevent displacement in a rearward direction, and I therefore pivot on each hinge of the front leaf a link 22. These links are provided with lateral projections 23 which are 35 adapted to engage in front of the guide bars 19. To facilitate the engagement of the projections 20 behind the guide bars 19, and the projections 23 in front of said bars, I 40 provide each of the vertical guide bars 19 with the forwardly inclined upward extension 24.

45 It will be noted that when the restraining bars 21 are in their normal operative position, they substantially meet the upper ends of the vertical guide bars 19, and the book of leaves is held in position with its pivot pins 4 lying between the pair of stops 7 and one of the pairs of stops 6. The leaves may 50 then readily be turned up or down as may be necessary. To remove the book of leaves, it is necessary to raise the restraining bars. The table will then lift sufficiently far to raise the pivots 4 above the tops of the lugs 55 6, behind which they have been engaged. The book of leaves is then tipped forward and the projections 20 and 23 of the front leaf pulled off the inclined extensions 24 of the vertical guides, when the book is free. 60 By a reversal of the process a book is readily placed in position.

While any suitable means may be provided for adjusting the restraining bars, I prefer to arrange them to slide vertically on 65 the guides 25 and 26, which are suitably sup-

ported at opposite sides of the casing. The guides 26 are preferably formed as round bars and the restraining bars are provided with lugs 27 sliding thereon. The restraining bars, it will be noted, are held in contact with the flat faces of the guides 25 by the guides 26. Each restraining bar is provided with a slide 28 connected thereto by pin and slot connections. When a restraining bar is in its normal operative position, 70 the rear end of the slide engages below a lug 29 stamped out of the rear guide 25.

Pivoted near the forward end of each restraining bar is a latch 30, which latch has a pin and slot connection with the slide 28 80 so that by the operation of the slide, the latch may be moved into or out of position to engage a shoulder 31 formed at the lower end of the front guide 25. A coil spring 32 is connected at one end to the restraining bar and at the other end to the pin 33 secured to the slide 28, so that the tension of the spring tends to move the slide to a position for its rear end to engage beneath the lug 29 and also to cause the slide to throw 90 the latch 30 to the position in which it engages the shoulder 31. The slide is preferably formed of sheet metal and the outer end is bent to form an inclined lug 34 forming convenient means whereby the slide may be 95 operated or used to push down the restraining bar when it is desired to restore it to its normal operative position.

As the use of the projections 23 tends to raise the first leaf at its hinged edge above 100 the top of the table 9, I form at opposite sides of the table raised bosses 35 adapted to engage the outer part of the front leaf when it is turned down so that the said leaf will be held substantially parallel to the top of 105 the table. In order that the front edge of the leaves may remain exposed when more or less of the book is in horizontal position, the front of the lower part of the casing is cut out and as an opening would be left 110 when the table is in an raised position, I secure to the forward edge of the table a roller curtain 36 of ordinary type, which passes around the guides 37.

It will be noted that, as the pivot pins 4 115 are held in substantially fixed position, when only one leaf is up the leaf is inclined somewhat rearwardly, whereas when all the leaves are up, the front leaves are inclined somewhat forwardly. I therefore prefer to 120 extend the sides of the casing forwardly, their front edges inclining from substantially the location of upper ends of the vertical guides 19. The sides of the leaves of the book, when they are all in the upright 125 position, are thus all covered, while the sides of the casing do not overlap in any way the leaves when the latter are in horizontal position.

The apparatus as shown is adapted for use 130

with books containing fewer or more leaves than those shown, it being merely necessary to shift the position of the stops 7 as hereinbefore described.

5 What I claim as my invention is:—

1. In an account file, the combination of a plurality of account holding leaves hinged together so that they may be turned to substantially vertical or horizontal position; a 10 resiliently supported, vertically movable table on which the leaves are supported; pins projecting from the hinges of the leaves at each side; a restraining bar at each side movable to and from its normal position in 15 which it is engaged by the said pins to prevent their vertical movement; and supporting means engageable by the upper part of the back leaf to prevent said leaf falling backward.

2. In an account file, the combination of a plurality of account holding leaves hinged together so that they may be turned to substantially vertical or horizontal position; a 20 resiliently supported, vertically movable table on which the leaves are supported; pins projecting from the hinges of the leaves at each side; a restraining bar at each side movable to and from its normal position in 25 which it is engaged by the said pins to prevent their vertical movement; a projection at each side of the back leaf of the book adjacent its upper edge; and stops, the outer 30 faces of which are engageable by said projections to prevent the back leaf falling 35 backward.

3. In an account file, the combination of a plurality of account holding leaves hinged together so that they may be turned to substantially vertical or horizontal position; a 40 resiliently supported, vertically movable table on which the leaves are supported; pins projecting from the hinges of the leaves at each side; a restraining bar at each side movable to and from its normal position in 45 which it is engaged by the said pins to prevent their vertical movement; a projection at each side of the back leaf of the book adjacent its upper edge; and bearings for said

projections open at their upper side whereby when the restraining bars are raised the projections may lift out of the bearings. 50

4. An account file constructed as set forth in claim 1 provided with a vertical guide bar at each side of the table extending up substantially to the restraining bars, when the latter are in normal position and provided with short forwardly inclined extensions at their upper ends, the projections from the hinges of said leaves lying behind said guide bars when the leaves are horizontal; links 60 pivotally connected with the front leaf, one at each side at its hinges; and a projection on each link engaging on the front side of the adjacent guide bar.

5. An account file constructed as set forth 65 in claim 3 in which the open bearings for the upper projections of the back leaf are adjustable to a plurality of positions at different distances from the front of the apparatus. 70

6. An account file constructed as set forth in claim 3 in which the bearings for the upper projections of the back leaf comprise bars suitably supported in a fore-and-aft position, and a plurality of short lugs 75 secured to said bars at different distances from the front of the apparatus.

7. In an account file, the combination of a plurality of account holding leaves hinged together so that they may be turned to substantially vertical or horizontal position; a 80 resiliently supported, vertically movable table on which the leaves are supported; pins projecting from the hinges of the leaves at each side; a restraining bar at each side 85 adapted to be engaged by the said pins to prevent their vertical movement; and supporting means engageable by the upper part of the back leaf to prevent said leaf falling backward. 90

Signed at Trenton, Ontario, this eighteenth day of February, 1920.
